CLAIM

The ornamental design for a finger scanner, as shown and described.

DESCRIPTION

2. Finger scanner
2.1 : Perspective
2.2 : Top
2.3 : Bottom
2.4 : Right
2.5 : Left
2.6 : Front
2.7 : Back

The design consists of the features of shape, ornament, pattern and configuration of a finger scanner shown in the reproductions; the broken lines illustrate portions of the finger scanner that form no part of the claimed design.
